2 SHEETS—SHEET 2.

UNITED STATES PATENT OFFICE.

HARRY GROVES, OF BELLINGHAM, WASHINGTON.

AUTOMATIC GARAGE-DOOR.

1,394,728.

Specification of Letters Patent. Patented Oct. 25, 1921.

Application filed November 15, 1920. Serial No. 424,174.

To all whom it may concern:

Be it known that I, HARRY GROVES, a citizen of the United States, and a resident of Bellingham, in the county of Whatcom and State of Washington, have invented new and useful Automatic Garage-Doors, of which the following is a specification.

My invention relates to improvements in automatic garage doors, and the objects of 10 my invention are: to provide suitably hung garage doors and mechanism to operate the same made operable by the entering and departing automobiles, to provide for the operation of said doors by hand without the 15 intervention of said mechanism, to provide for the automatic fastening and unfastening of said doors, to cause the automatic opening and closing of the doors to be safe-guarded by slow and not resistless movements, to provide against the undesired automatic operation of the mechanism by passing 20 animals, to provide suitable locking mechanism, and other desirable conveniences as will more fully appear.

I attain these objects with the mechanism illustrated in the accompanying two sheets of drawings in which Figure 1 is a plan view of double garage doors with my operating mechanism connected thereto, Fig. 2 25 is a side elevation of Fig. 1, Fig. 3 is a separated, side-elevation view of parts shown in Figs. 1 and 2, Fig. 4 is the development of a cam, Fig. 5 is a rear elevation view of the garage doors drawn on a larger scale, Fig. 6 is a front elevation of one of said 30 garage doors, Fig. 7 is a plan view of a part of Fig. 5 in section on the line 7—7, Fig. 8 is an elevation of a part of Fig. 5 in section on the line 8—8, Fig. 9 is an enlarged 35 view of a part of Fig. 1, Fig. 10 is an elevation of Fig. 9 in section on the line 10—10, Fig. 11 is an enlarged view of a part of Fig. 1, and Fig. 12 is an elevation of Fig. 11 in section on the bent line 12—12.

Similar characters refer to similar parts 40 throughout. Certain parts are broken away for the lack of illustrating space or to show other parts hidden thereby. Other operative positions of moving parts are shown in 45 dotted outlines, and the direction of movement of some pivoted parts is shown by dotted circular arcs.

More particularly: 14 is the garage floor 50 and the street in front of the same. 14^a is 55 a door stop on said floor. 14^b is the floor

of a pit beneath the garage floor and between the doors, and below the operating platforms both in front of the garage and within the same. 14^c and 14^d are two stops fastened to floor 14^b.

15 is a plate covering an opening in floor 14, between the doors, through which access is afforded to the mechanism beneath.

16 is the front wall of the garage. 16^a is 60 a top door stop.

17 and 18 are garage double doors, said 65 doors are swingably mounted on or with vertical shafts 20 and 21 respectively.

19, 19 are spring door hinges, one used 70 on each of doors 20 and 21, only one being shown. The illustration shows a well-known form of spring hinge in which 19 is the housing, 19^a is a block bearing on the spring and, through the medium of a roller, on an oval boss, 19^b is a helical spring bearing 75 under compression on block 19^a, 19^c is an oval boss rigidly mounted on shaft 20 having a groove at each quadrant to seat said roller, and the purpose of the hinge is to automatically return the door to a quadrant 80 position in rotation and to provide a resilient and not positive connection between the door and its shaft.

20 and 21 are vertical shafts on which 85 doors 17 and 18 are respectively mounted. Each door is free to turn about its shaft except for the opposition of spring 19^b: the normal setting of said door on its shaft is localized to one of the shaft quadrants by said spring, which localization is sufficient 90 to cause the door to turn with its shaft under ordinary operative conditions. 20^b and 21^b are spur gears mounted fixed near the lower ends of shafts 20 and 21 respectively.

22, 22 are bearings fastened to garage 95 front 16 for mounting the upper ends of shafts 20 and 21, only one of said bearings being shown in Fig. 5.

23 and 24 are vertical locking bars for 100 doors 17 and 18 respectively, said bars have hooked lower ends 23^a and 24^a respectively. 23^b, 23^b and 24^b, 24^b are slideways fastened 105 to doors 17 and 18 for bars 23 and 24 respectively. 23^c and 24^c are studs in front 16 for mounting upper door latches 23^e and 24^e respectively. 23^d and 24^d are beveled strike surfaces on latches 23^e and 24^e respectively. 23^f and 24^f are counterweights on latches 23^e and 24^e respectively. 23^g and 110

24^g are stops to limit downward movement of top latches 23^e and 24^e. 23^h and 24^h are toothed racks on bars 23 and 24.

25 and 26 are segmental spur gears respectively engaged with racks 23^h and 24^h and mounted for rotation on bolts 25^a and 26^a on doors 17 and 18 respectively. 25^b and 26^b are counterweights on gears 25 and 26 respectively, and are heavy enough to 10 overbalance the weight of said bars and said top door latches and normally bear on stop pins 25^d and 26^d respectively. 25^e and 26^e are stop pins to limit the upward movement of said counterweights. 25^e and 26^e are 15 handles on said counterweighted gears.

27 and 28 are locks respectively fastened to doors 17 and 18 and each has a bolt suited to engage with a notch in one of said counterweights when it is against its lower 20 stop.

29 is a platform mounted in an opening through floor 14 in front of the garage doors on the exterior and its top is normally flush with said floor. 29^a, 29^b, 29^c, 29^d are four 25 studs pendant from the lower side of platform 29 mounted in slideways 31^a in cross bars 31, 31.

30 is a platform mounted in an opening through floor 14 within the garage and to 30 the rear of said garage doors and its top is normally flush with said floor. 30^a, 30^b, 30^c, 30^d are four studs pendant from the bottom of platform 30 mounted in slideways 32^a in crossbars 32, 32. 29^b and 30^b are 35 central lugs on the bottom of said platforms.

Said four crossbars 31 and 32 are fastened to the lower side of floor 14 and, besides providing slideways for said studs, furnish stops for the lowest positions of said platforms.

33 and 34 are links pivoted to lugs 29^b and 30^b and to dashpot pistons 35 and 36 respectively. Said dashpot pistons are mounted for reciprocation in dashpots 37 and 38 respectively fastened to floor 14^b beneath platforms 29 and 30. 37^a and 38^a are two valves each controlling an air outlet from cylinders 37 and 38.

39 and 40 are two bearing brackets respectively fastened to floor 14^b beneath platforms 29 and 30.

41, 43 and 45 are the arms of a T crank pivotally mounted on bracket 39. Arm 43 has a slot pivotally connected with link 33. And arm 45 carries an adjustable counterweight 45^a, normally bearing on stop 14^c.

42, 44 and 46 are the arms of a T crank pivotally mounted on bracket 40. Arm 44 has a slot pivotally engaged with link 34. 60 Arm 46 bears an adjustable counterweight 46^a, normally bearing on stop 14^d.

47 is a link one end of which is pivotally connected to the upper end of T crank arm 41 and the other end has slot 47^a engaged 65 with a pin 51^a on the upper end of double

crank 51. 47^b is an inclined-surface boss on the upper side of link 47.

48 is a link one end of which is pivotally connected to the upper end of T crank arm 42 and its other end has slot 48^a engaged 70 with pin 51^b on the lower end of double crank 51. Link 48 extends beyond slot 48^a and is bent upward to lay along side of link 47 and bears on its upper end inclined-surface boss 48^b.

49 is a bearing pedestal fastened to floor 14^b beneath the middle of floor plate 15. 49^a is a stop pin in one of the brackets of pedestal 49 to limit the movement of double crank 51.

50 is a shaft mounted for revolution in bearings on pedestal 49.

51 is a double crank mounted fixed on shaft 50, it has crank pins 51^a and 51^b respectively engaged with slots 47^a and 48^a 85 in links 47 and 48 and normally bears against stop 49^a. Crank 51 has a hub to which is fastened and around which is wound a small cable fastened also to counterweight 51^d which normally retains crank 90 51 against stop 49^a. 51^c is a pawl pivoted to the upper end of crank 51 in engagement with ratchet 52.

52 is a ratchet wheel mounted rigidly on shaft 50 near crank 51.

53 is a cam disk fixedly mounted on shaft 50, the development of which is shown in Fig. 4; where two contiguous quadrants, AB and BC are plain and cause no operative movement, and contiguous quadrants CD 100 and DA are deflected and cause an out and return movement respectively.

54 is a shifting bar mounted for endwise movement on segmental spur gears 56 and 57 and on bosses 56^a and 57^a concentric thereon. 105 On each end of said bar is an oval 54^b and 54^c which operate on said bosses as slideways. On the interior of oval 54^b are diagonally placed tooth notches 54^d and 54^e, see Figs. 1, 11 and 12. Similar tooth notches are 110 similarly placed in oval 54^c, only one of which, 54^e is shown, the other being occupied by stud 55. 54^a is a notch in bar 54 engaging cam 53.

55 and 55 are tooth studs engaged in 115 tapped holes 55^a and 55^b in gears 56 and 57, in engagement with said tooth notches 54^d and 54^e. Said studs are also engageable in holes 55^a and 55^b, where they are placed when engaged with tooth notches 54^d and 54^e.

56 and 57 are segmental gears mounted on studs 56^b and 57^b on pedestals 58 and 58 and engaged with spur gears 20^b and 21^b on door shafts 20 and 21. Nuts on tooth studs 55, 55 retain bar 54 in place on said gears.

58 and 58 are two bearing pedestals fastened to floor 14^b beneath shafts 20 and 21.

59, 59 are bearing boxes fastened beneath floor plate 15 and mount shaft 60.

61 is a counterweight mounted on shaft 139

60 to bear on inclined-surface lugs 47^b and 48^b.

62 and 63 are two lower door latches mounted for revolution on shaft 60 to engage doors 17 and 18, respectively, when closed. Said latches have hook ends engageable with bars 23 and 24. They also have counterweights 62^a and 63^a, respectively, bearing on counterweight 61.

10 In operation: Assuming doors 17 and 18 closed and fastened by lower latches 62 and 63 and upper latches 23^e and 24^e, as shown, but not locked. The front wheels of an automobile to be driven in the garage 15 pass on to platform 29. Counterweight 45^a has been proportioned and adjusted on arm 45 to be overbalanced by the weight on said front wheels and said weight carries the platform downward to rest on cross-bars 20 31, meanwhile causing arm 45 and weight 45^a and arm 41 to move to their dotted-line position, moving link 47 toward the right, first causing boss 47^b to raise counterweight 61 and with it counterweights 62^a and 63^a, 25 thus depressing lower, door latches 62 and 63 which, being engaged with bars 23 and 24, carry them downward and permit upper, door latches 23^e and 24^e to rise, thus fully 30 releasing doors 17 and 18 from their fastenings; and then, slot 47^a having moved far enough to bear on pin 51^a, crank 51 is carried to the right and with it rotates ratchet 52 and cam 53 through quadrant DC, which cam movement moves bar 54 to its dotted-line position and operates gears 56 and 20^b, and 57 and 21^b to swing doors 17 and 18 open through a quadrant. These movements of the several operative parts concerned are made slowly and evenly by the 40 action of dash pot 37. In case the doors meet an obstacle to their movement they can be stopped by a moderate force because of the relief provided by door spring hinge 19. When said front wheels have passed

45 from platform 29 it is caused to rise to its position flush with floor 14 by the operation of counterweight 45^a. Also crank 51 is returned to its full-line position by the operation of counterweight 51^a. When the automobile's rear wheels pass on to platform 29 the same operative movements as before are caused as far as and including cam 53. But since the cam quadrant in engagement with bar 54 during this movement is CB, which 55 is plain, bar 54 is not moved and the doors remain open as before. Said automobile passes through said open doors into the garage and its front wheels pass on to platform 30 which is caused to operate in every 60 way similar to platform 29, above described, together with its connected mechanism. In this case link 48 is moved toward the left, and although the doors are open the lower door latches are depressed by the 65 movement of boss 48^b beneath counter-

weight 61. Also the other movements occur as far as said cam wheel which is caused to rotate through quadrant BA which, being plain, causes no movement in bar 54. The front wheels pass from platform 30, 70 and it, together with its connected mechanism return to their full-line positions under the weight of counterweight 46^a. Then the rear wheels pass on to said platform, when it is again depressed and causes 75 through intervening mechanism as described, cam wheel 53 to rotate through quadrant AD which moves bar 54 to its full-line position and closes doors 17 and 18 which are automatically fastened by latches 80 62, 63 and 23^e, 24^e.

An automobile leaving the garage must pass first over platform 30 which will operate to open the doors as before because of the successive cam movements, as the front 85 and rear wheels in turn pass over platform 30 and then platform 29, said cam is moved through quadrants DC, CB, BA and AD in turn, and said doors will be opened and remain open until said automobile has passed 90 from platform 29 the passing of the rear wheels over which closed said doors.

The next automobile to approach said doors, whether from without or from within, will operate said doors as already described. 95

In case it is desired to operate said doors by hand without regard for the automatic mechanism described, the doors are opened and closed as any others hung on spring 100 hinges, and said mechanism is not disturbed.

By engaging tooth studs 55, 55 in holes 55^b, 55^b and in notches 54^e, 54^e doors 17 and 18 are caused to open outward. And by making this change of tooth stud in one 105 gear and oval only, the door operated by said gear will open outwardly, while the other door will open inwardly.

Doors 17 and 18 can be separately locked and unlocked from without or within, when 110 closed, by using locks 27 and 28 as usual.

As shown, the doors move through one quarter revolution for each operative quadrant movement of the cam wheel. The mechanism could as well be made to cause a greater or less door movement for each 115 quadrant movement of the cam.

My improvement is very well adapted for automatically operating gates and the like. 120

Having thus fully disclosed my invention what I claim is new and desire to secure by Letters Patent is,—

1. In an automatic, door-operating device in combination, a swingable door, two depressible platforms in the way closed by said door, one of said platforms on each side of said door, automatic means to raise said platforms after being depressed, and means adapted to swing said door a pre- 125 130

- determined part of a rotation once forward and once backward for each four consecutive times either or alternately both of said platforms are depressed, said first depressing adapted to cause said door to swing open, said second and third depressings adapted to have no operable effect on said door, and said fourth depressing adapted to close said door.
- 10 2. In an automatic, door-operating device in combination, a swingable door, two depressible platforms in the way closed by said door, one of said platforms on each side of said door; automatic means to raise said platforms after being depressed; means to swing said door a predetermined part of a rotation once forward and once backward made operative by each four consecutive depressings of said platforms or either of them, said first depressing adapted to cause said door to swing open, said second and third depressings adapted to have no operable effect on said door, and said fourth depressing adapted to close said door; automatic means to latch said door on closing; and automatic means, operable by the door operating means, to unlatch said door before opening.
3. In an automatic, door-operating device in combination, a swingable door; two platforms, depressible by not less than a predetermined weight, in the way closed by said door, one on each side of said door; automatic means to raise said platforms after being depressed; and means to swing said door a predetermined part of a rotation once forward and once backward made operative by each four consecutive depressings of said platforms or either of them, said first depressing adapted to cause said door to swing open, said second and third depressings adapted to have no operable effect on said door, and said fourth depressing adapted to close said door.
- 45 4. In an automatic, door-operating device in combination, two, swingable, coöperating doors; two platforms, depressible by not less than a predetermined weight, in the way closed by said doors, one on each side of said doors; automatic means to raise said platforms after being depressed; and means to simultaneously swing said doors a predetermined part of a rotation once forward and once backward made operative by each four consecutive depressings of said platforms or either of them, said first depressing adapted to cause said doors to swing open, said second and third depressings adapted to cause no operative effect on said doors, and said fourth depressing adapted to close said doors.
5. In an automatic, door-operating device in combination, a door shaft mounted for rotation; a door swingably mounted on said shaft and engaged therewith by resilient, non-positive means; two platforms, depressible by not less than a predetermined weight, in the way closed by said door, one on each side of said door; automatic means to raise said platforms after being depressed; and means to rotate said door shaft a predetermined part of a rotation once forward and once backward made operative by each four consecutive depressings of said platforms or either of them, said first depressing adapted to cause said door to swing open, said second and third depressings adapted to have no operative effect on said door, and said fourth depressing adapted to close said door.
6. In an automatic, door-operating device in combination, two, coöperating door shafts mounted for rotation; a door mounted swingably on each of said shafts and engaged therewith by resilient, non-positive means; a catch for each of said doors automatically operated by closing said doors and automatically operable to release said doors by the door-operating mechanism, and operable without using said mechanism; two platforms, depressible by not less than a predetermined weight, in the way closed by said doors, and one on each side of said doors; automatic means to raise said platforms after being depressed; and means to swing said door shafts each a predetermined part of a rotation once forward and once backward made operative by each four consecutive depressings of said platforms or either of them, said first depressing adapted to cause said doors to swing open, said second and third depressings adapted to have no operative effect on said doors, and said fourth depressing adapted to close said doors.
7. In an automatic, door-operating device in combination, a swingable door; two platforms depressible by not less than a predetermined weight, one on each side of said door; automatic means to raise said platforms when depressed; and slowly operable means to swing said door made operative by each of two descents of said platforms or either of them, following two descents which are non-operative to swing said door.

HARRY GROVES.
